UNITED STATES PATENT OFFICE.

WILLIAM MEHN, OF CORYDON, KENTUCKY.

ANTIRATTLER FOR SWINGLETREES.

No. 888,183.

Specification of Letters Patent.

Patented May 19, 1908.

Application filed September 10, 1907. Serial No. 392,134.

To all whom it may concern:

Be it known that I, WILLIAM MEHN, a citizen of the United States, residing at Corydon, in the county of Henderson and State of Kentucky, have invented a new and useful Anti-rattler for Swingletrees, of which the following is a specification.

The invention relates to improvements in anti-rattlers for swingletrees.

10 The object of the present invention is to improve the construction of anti-rattler devices for swingletrees, and to provide a simple, strong and durable device, designed for use on various kinds of one horse vehicles, 15 and adapted to permit the whiffletree to be screwed tightly against the cross bar of a pair of shafts, and capable, as the bearing or wear plates become worn, of automatically taking up the wear and of holding the 20 swingletree firmly against the cross bar, whereby the swingletree is prevented from rattling.

With these and other objects in view, the invention consists in the construction and 25 novel combination of parts hereinafter fully described, illustrated in the accompanying drawing, and pointed out in the claims hereto appended; it being understood that various changes in the form, proportion, size and 30 minor details of construction, within the scope of the claims, may be resorted to without departing from the spirit or sacrificing any of the advantages of the invention.

In the drawing:—Figure 1 is a plan view of 35 an anti-rattler, constructed in accordance with this invention and shown applied to a swingletree. Fig. 2 is a central vertical sectional view, taken longitudinally of the swingletree. Fig. 3 is a transverse sectional 40 view of the same. Fig. 4 is a detail perspective view of the anti-rattler spring. Fig. 5 is a detail view of one of the keepers for the ends of the spring.

Like numerals of reference designate corresponding parts in all the figures of the drawing.

1 designates a swingletree, pivotally mounted in the usual manner on the upper face of a cross bar 2 by means of a bolt 3, 50 which pierces the swingletree and the cross bar, suitable wear or bearing plates 4 and 5 being interposed between the swingletree and the cross bar. These wear or bearing plates, which may be of any preferred construction, 55 do not constitute a portion of the present

invention and a detail description thereof is deemed unnecessary.

The cross bar and the swingletree are arranged within a substantially U-shaped brace 6, consisting of upper and lower arms 60 7 and 8 and a connecting rear portion, as clearly illustrated in Fig. 3 of the drawing. The upper and lower arms 7 and 8 are spaced a part to receive the swingletree and the cross bar. The lower arm 8 fits against the lower 65 face of the cross bar, and the upper arm is provided at its lower face with a depending integral collar or sleeve 9, which spaces the upper arm of the brace from the swingletree. The washer 10 is preferably interposed be- 70 tween the lower end of the spacing collar or sleeve and the upper face of the swingletree to prevent the latter from being worn by the former. This construction permits the nut 11 of the bolt to be screwed tightly against 75 the lower face of the lower arm of the brace, and it enables the pivotal connection between the swingletree and the cross bar to be screwed as tight as that of an ordinary swingletree.

When the wear or bearing plates become worn, the wear or bearing plate of the swingletree is held firmly against the wear or bearing plate of the cross bar by means of a bowed spring 12, having a central enlarged 85 portion and provided therein with an opening 13 to receive the spacing collar or sleeve. The spacing collar or sleeve passes through the opening 13 and the central portion of the spring bears against the lower face of the upper arm 7 of the brace. The ends of the spring are received within seats or recesses 14 of keepers 15, consisting of plates or pieces, provided with spaced upwardly extending flanges 16. The keepers, which may 95 be stamped, or otherwise formed from a single piece of sheet metal, are secured by suitable fastening devices 17 to the upper face of the swingletree at opposite sides of the pivot bolt, and the ends 18 of the spring are 100 reduced and provided with straight side edges to fit between the projecting flanges 16 of the keepers. The keepers maintain the spring in proper position with relation to the swingletree and prevent any displacement 105 of the spring through the oscillation of the swingletree, and they also prevent the ends of the spring from marring the finish of the swingletree. A spring of any desired size and strength may be employed to suit the 110

character of the vehicle on which it is to be used. The bolt, when screwed tight, presses the collar or sleeve 9 down on the swingletree and thus snugly holds it to the cross bar, 5 while the spring bearing against the brace prevents the parts from rattling when wear takes place. By this arrangement, the nut of the bolt may be screwed as tight as desired without affecting the operation of the 10 spring.

Having thus fully described my invention, what I claim as new and desire to secure by Letters Patent, is:—

1. In a device of the class described, the 15 combination with a cross bar, and a whiffletree, of a bolt piercing the same, a brace having upper and lower arms extending across the upper face of the whiffletree and the lower face of the cross bar and secured to the 20 same by the said bolt, a collar spacing the upper arm of the brace from the whiffletree and forming a rigid support for the said upper arm, and a spring interposed between the upper arm of the brace and the upper face of 25 the whiffletree for holding the latter tightly against the cross bar.

2. In a device of the class described, the 30 combination with a cross bar, and a whiffletree, of a bolt piercing the same, a substantially U-shaped brace having upper and lower arms extending across the lower face of the cross bar and the upper face of the whiffletree and provided with an integral depending spacing collar interposed between 35 the upper face of the whiffletree and the upper arm of the brace and forming a rigid support for the said upper arm, and a bowed spring having a central opening to receive the collar and interposed between the upper 40 portion of the brace and the upper face of the whiffletree.

3. In a device of the class described, the 45 combination with a whiffletree, and a cross bar, of a bolt piercing the same, a brace receiving the cross bar and the whiffletree,

rigid means for spacing the upper portion of the brace from the whiffletree, a bowed spring located at the said spacing means and interposed between the upper portion of the brace and the swingletree, and keepers mounted on 50 the upper face of the whiffletree and provided with recesses receiving the ends of the spring.

4. In a device of the class described, the combination with a whiffletree, and a cross bar, of a bolt piercing the same, a brace receiving the cross bar and the whiffletree, rigid means for spacing the upper portion of the brace from the whiffletree, a bowed spring located at the said spacing means and interposed between the upper portion of the 60 brace and the swingletree, and spaced keepers mounted on the upper face of the whiffletree and provided with upwardly extending spaced flanges forming intervening recesses to receive the ends of the spring. 65

5. In a device of the class described, the combination with a cross bar, and a whiffletree, of a bolt piercing the same, a substantially U-shaped brace receiving the cross bar and the whiffletree and extending across the 70 lower face of the former and the upper face of the latter and secured to the same by the bolt and provided at the top with a spacing collar interposed between the brace and the upper face of the whiffletree and forming a 75 rigid support for the said brace, a bowed spring having a central opening to receive the collar and engaging the upper portion of the brace, and spaced keepers mounted on the upper face of the whiffletree at opposite 80 sides of the brace and having upwardly projecting flanges spaced apart and forming recesses to receive the ends of the spring.

In testimony, that I claim the foregoing as my own, I have hereto affixed my signature 85 in the presence of two witnesses.

WILLIAM MEHN.
